IGNITION INTERRUPTER

Harry R. Kitts, Green Bay, Wis.

Application March 26, 1951, Serial No. 217,564

15 Claims. (Cl. 200—31)

1

This invention relates generally to switch mechanisms, and more particularly to improvements in switch mechanisms of the interrupter type used in ignition systems of automotive engines.

With present ignition systems, full and complete combustion of the gas charge is not always assured. The result is loss of power and fouling of the engine, particularly of the spark plugs.

In some instances attempts have been made to overcome these advantages by applying several spark plugs to a cylinder, or by providing an interrupting device with several sets of breaker points whose main function is to provide a succession of distinct sparks for each gas charge in each cylinder, so that if one spark will not cause full and complete combustion, a second or follow-up spark will complete the combustion.

These solutions have not been practical because of their complexity and resulting inadaptability to the present day standardized ignition system designs.

The purpose of this invention is to provide a "multiple-spark" ignition interrupter apparatus, capable of providing a succession of sparks for each gas charge in each cylinder, embodying only a few additional simple and efficient parts which can be readily assembled and applied to conventional standardized automobile ignition systems without requiring any changes in the construction, arrangement or design of said conventional system.

An object of this invention is to provide a multiple-spark ignition system interrupter that is very easily adapted to the conventional standardized ignition apparatus.

Another object of this invention is to provide a multiple-spark ignition system interrupter that is interchangeable with the conventional interrupters presently used.

Still another object of this invention is to provide a multiple-spark ignition system that is controlled by one main breaker arm structure.

Yet another object of this invention is to provide a multiple-spark ignition system interrupter having a main breaker arm and auxiliary breaker arm means mounted thereon for actuation therewith.

A further object of this invention is to provide a multiple-spark ignition interrupter structure which maintains a constant maximum air gap between a second set of contact points regardless of the wear of a common cam follower.

A still further object of this invention is to provide a multiple-spark ignition interrupter structure which maintains a constant maximum air gap between a second set of contact points regardless of the adjustable positionment of main breaker points connected therewith.

Yet a further object of this invention is to provide a multiple-spark ignition interrupter

2

structure which supplies a follow-up spark at a fixed crank angle relation to the normal basic spark regardless of wear of a common cam follower.

Another object of this invention is to provide a multiple-spark interrupter that does not bounce at high speeds.

Other objects and many of the attendant advantages of this invention will be readily appreciated as the same becomes better understood by reference to the following detailed description when considered in connection with the accompanying drawings in which like reference numerals designate like parts throughout the figures thereof and wherein:

Figs. 1 and 2 illustrate front elevational views of the interrupter structure and cam showing different relative positions of the elements of the mechanisms;

Fig. 3 is an enlarged sectional view taken along line 3—3 of Fig. 1; and

Fig. 4 is an electrical diagram showing the circuit connections of the interrupter embodied in a conventional simplified ignition system.

Referring now to the drawings, wherein like reference characters designate like or corresponding parts throughout the several views, there is shown in Fig. 1 an interrupter device generally indicated by reference numeral 9, comprising a plate or disc 10, preferably made of an insulating material, which is adapted to be rotatably controlled by governor means, mechanical or vacuous, or the like (not shown), to effect an automatic advance or retard of the sparking, in the conventional auto ignition system manner. Said disc 10 is centrally apertured to receive a distributor or cam shaft 11 therethrough, to which a hexagonal cam 12 is rotatively-rigid secured and about which the disc is revolvable for ignition timing purposes, in the conventional ignition system manner. The six angle point portions of said cam serve as cam lobes.

A first main breaker arm 13 is pivotally connected at one end, to disc 10 as by means of pin 14 fixed to disc 10; the other end of said arm is provided with a contact point 15 secured thereto as by spot welding. Intermediate the ends of said arm is riveted a cam follower or rubbing block 16 which is disposed to slidably contact the cam 12.

Arm 13 is biased toward cam 12 by means of initially tensioned leaf spring 17 having one end riveted to the under side of arm 13 and the other end abutting against a fixed bracket 18 secured to disc 10 by means of screw 19. The spring 17 is held in abutment against the bracket by means of an elongated bolt 21 and nut 22. A thumb screw 23 is threadedly engaged with the free end of said bolt to provide a binding post arrangement generally indicated at 20 for the connection thereto of an electrical conductor such as that

forming one side of an ignition system shown in Fig. 4.

A second bracket 24, preferably conductive, is secured to the disc 10 by means of screws 25 and 26. Elongated screw openings 40 are provided in said bracket to allow for bracket positional adjustability in aid of contact point gap settings hereinafter described. Said bracket 24 has a conductive, integrally formed arm 27 which supports a fixed contact point 28 secured thereto as by spot welding. Said contact point 28 is operatively disposed relative to companion contact point 15.

Movable contact point 15 is normally held in engagement with fixed contact point 28 by means of biasing spring 17 acting through arm 13. Rotatable cam 12 actuates arm 13 through means of rubbing block 16, thereby disengaging movable contact point 15 from fixed contact point 28 in the usual and conventional manner. It is obvious that a positional adjustment of bracket 24 not only varies the operational gap between main breaker points 15 and 28, but also varies the point of contact of the cam follower 16 on the lobes of cam 12.

Thus far the structure described is known to be old and conventional; the improvement thereon follows.

A second auxiliary limb or breaker arm 29 is cantilever supported on the back of arm 13 and disposed in the same radial general direction therewith; one end being fixed thereto as by spot welding and the other free ascending upwardly and being spaced therefrom. Said second arm 29 should preferably have elastic and resilient characteristics such as a leaf spring or the like. A contact point 31 is secured to the free end of arm 29 as by spot welding.

A cooperative fixed contact point 32, disposed to coat with movable contact point 31 and normally spaced therefrom, is mounted as by spot welding on a conductive supporting element 33 which in turn is bolted to bracket 24 by means of an elongated bolt 34 and nut 35. The bolt opening (not shown) through supporting element 33 is elongated to allow for some degree of positional adjustability of element 33 and its attached contact point 32. A thumb screw 36 is threadedly engaged on the free end of said bolt 34 to provide another binding post arrangement generally indicated at 38 for the connection thereto of an electrical conductor such as that forming the other side of the ignition system shown in Fig. 4.

An L-shaped bracket 37, having one leg riveted to arm 13 and the other leg disposed toward and beyond the arm 29, carries a cam screw 38 disposed over arm 29. Said screw is threadedly engaged with said bracket and is disposed so that its cam head bears against the outer face of arm 29 for adjusting the air gap between associated contact points 31 and 32. A coil spring 39 is interposed between the supporting bracket 37 and the head of cam screw 38 to resist rotational displacement thereof.

Leaf spring arm 29 is preferably initially tensioned to normally bear against the cam 38. It is obvious that a rotation of cam screw 38 varies the air gap between cooperative contacts 31 and 32 through means of resilient limb 29.

It is to be noted that the relation of the cam 38 to the arm 29 is such that a clockwise movement of arm 13 will positively draw arm 29 clockwise along with it. In a counterclockwise movement there is no such positive drive connection.

This arrangement provides yieldable connecting means operative to normally limit relative movement of the limbs away from each other, but permitting free relative movement toward each other.

Fig. 4 shows a simplified wiring diagram of a conventional auto ignition system comprising two circuits—primary and secondary.

The primary is a low voltage ignition circuit energized by a generator 41 and a battery 42 in the usual manner. In series therewith is the primary coil 43 and the interrupter 9. A condenser 44 is connected across the contact points of the interrupter 9 to prevent arcing thereacross.

The secondary high voltage circuit consists of a series arrangement of the secondary coil 45, inductively related to said primary coil 43, and an associated distributor 46 adapted to be connected to spark plugs (not shown).

Operation: Assume the interrupter device to be connected in an ignition circuit as shown in Fig. 1, and further assume the cam member to rotate in the direction indicated by the arrow. In the normal position of rest shown in Figs. 1 and 4, the primary circuit is closed through abutting main breaker contacts 15 and 28 and the primary induction coil 43 is being properly saturated.

As the cam travels clockwise from this normal position the cam lobe 47 initially will raise arm 13 and disengage main breaker points 15 and 28 thereby opening the primary circuit. As a result thereof, the magnetic field built-up around coil 43 collapses rapidly. The rapid movement of collapsing lines of magnetic force induces a very high voltage in the secondary coil 45. This voltage is led to the distributor 46 where it directs the high voltage impulse first to one spark plug, then to another, and so on. The voltage being great enough to overcome the resistance at the gap between the spark electrodes, the circuit is completed to ground and the hot spark ignites the fuel mixture. The high voltage induced in this manner is momentary; and a surge occurs each time the magnetic field, established by current flow through the primary circuit, is rapidly collapsed.

Shortly after the breaking of associated breaker points 15 and 28, and before the high point on the lobe 47 is reached, cooperative breaker points 31 and 32 engage and close the primary circuit therethrough. This position of components is illustrated in Fig. 2. The closing of the primary circuit by these auxiliary points results in a current flow through primary coil 43 and a build-up of a magnetic field around it.

As the cam travel continues to the high point on the lobe 47, arm 13 continues to be raised, but arm 29 apparently is arrested because of the abutment of its auxiliary breaker points 31 and 32.

However, due to the resilient characteristics of arm 29 it deflects and bends, thereby allowing the full cam lift to operate without breakage of any of the associated components. In other words the cam continues to push-up and stress arm 29 to maintain engagement of contacts 31 and 32 for a preselected interval of time. Furthermore, it prevents bouncing of the resiliently mounted contact 31 against fixed contact 32.

It is to be noted that immediately after auxiliary breaker points 31 and 32 engage, any further cam travel toward its high point progres-

5

sively separates the cam screw 38 from its abutment with arm 29.

As the cam follower 16 moves down the other side of the cam lobe, from the high point thereon, said deflection and bending is slowly relieved until cam screw 38 again abuts auxiliary arm 29, at which time the deflection is fully relieved.

Continued motion down the cam results in a disengagement of the auxiliary breaker points 31 and 32 through means of the positive drive connection of the cam screw 38 against auxiliary arm 29.

The disengagement of auxiliary breaker points 31 and 32 results in a breaking of the primary circuit. Consequently, the magnetic field built up around coil 43 collapses rapidly and induces a high voltage pulse in the secondary coil 45. This pulse is made available to the spark plugs as described above.

A further travel of the cam results in the restoration of the associated mechanism elements to their original normal position shown in Fig. 1, wherein breaker points 15 and 28 are re-engaged in preparation for another saturation of primary coil 43.

This cycle of events is repetitive.

It is preferred that the cam and the associated interrupter components be space related so that the auxiliary or second spark follows the main spark by approximately 20 degrees of crank angle.

It is to be noted that the interval of time allowed for the coil build-up attendant to the second spark is measured by the time lapse between the make and the break of coating contact points 31 and 32. In other words, it is the time lapse during which the cam lobe exerts a bending influence on arm 29 as when the follower moves upwardly on one side of the cam, commencing from a point corresponding to the engagement of auxiliary breaker points 31 and 32, thence over the high point of the cam, and thence downwardly on the other side of the cam to a point corresponding to the disengagement of said contact points 31 and 32.

It is preferred that the cam and the associated interrupter components be space related so that this coil build-up time interval is approximately 15 degrees of crank angle. This permits a sufficiently long period of closure to insure proper saturation of the induction coil to give a proper second spark.

When this improved interrupter arm mechanism is substituted for the interrupter mechanism in the conventional interrupter, it has been found that substantially proper time and space relations are achieved by adjusting supporting bracket 24, downwardly, until ten thousandths (0.010) inch obtains between the cam and its follower when the apparatus is in its normal position of rest as shown in Fig. 1.

The characteristic features of this improved multiple-spark interrupter are, a structure that is very easily adapted to the conventional ignition apparatus; an interrupter structure that is interchangeable with the conventional interrupter without effecting the design, operation or function of said conventional interrupter; a multiple limb interrupter arm that is controlled by one main breaker arm; and finally an interrupter structure which supplies a follow-up spark at a fixed crank angle relation to the normal basic spark regardless of wear of the common cam follower.

Obviously many modifications and variations of the present invention are possible in the light of

6

the above teachings. It is therefore to be understood, that within the scope of the appended claims, the invention may be practised otherwise than as specifically described.

5. What is claimed and desired to be protected by Letters Patent of the United States is:

1. An interrupter, comprising: an interrupter arm comprising two spaced limbs one of which is resilient; a contact on each of said limbs; electrically connected fixed contacts operatively disposed relative to said aforementioned contacts, a set of cooperative contacts being normally engaged and another set of cooperative contacts being normally spaced; means interconnecting said limbs operative to normally limit relative movement of the limbs away from each other but permitting free relative movement toward each other; and means for actuating said interrupter arm, said actuating means being adapted to maintain an engagement between the cooperative contacts identified with the resilient limb for a pre-selected interval of time.

2. An interrupter, comprising: a first interrupter arm carrying a contact; a second resilient interrupter arm carrying a contact, mounted on said first interrupter arm in spaced relation thereto; a supporting member; a pair of electrically connected fixed contacts mounted on said supporting member and operatively disposed relative to said aforementioned contacts, the fixed contact associated with the first arm contact being normally engaged therewith, and the fixed contact associated with second arm contact being normally spaced therefrom; means interconnecting said first and second interrupter arms operative to normally limit the spaced relation therebetween but permitting a free relative movement toward each other; and means for actuating said combined arm structure; said actuating means being adapted to continue to drive said structure after the second arm contact engages with its associated fixed contact.

3. An interrupter, comprising: a first interrupter arm carrying a contact; a second resilient interrupter arm carrying a contact, mounted on said first arm in spaced relation thereabove; a supporting member; a pair of electrically connected fixed contacts mounted on said supporting member and operatively disposed relative to said aforementioned contacts, the set of associated contacts identified with the first arm being normally engaged, and the set of associated contacts identified with the second arm being normally spaced; control means supported by said first arm operative to normally limit the spaced relation of said arms, but permitting free relative movement of the arms toward each other; and means for actuating said combined arm structure, said actuating means being adapted to maintain an engagement between the associated contacts identified with the second arm for an interval of time.

4. An interrupter, comprising: a first interrupter arm carrying a contact; a second resilient interrupter arm carrying a contact, mounted on said first arm and having its free end disposed in spaced relation above the free end of said first arm; a supporting member; a pair of electrically connected fixed contacts mounted on said supporting member operatively disposed relative to said aforementioned contacts, the set of associated contacts identified with the first arm being normally engaged, and the set of associated contacts identified with the resilient arm being normally spaced; control means mounted on said

first arm operative to normally limit the maximum spaced relation between said arms but permitting a free movement of the resilient arm toward the first arm, said resilient arm being tensioned against said control means; and means for actuating said first arm, said actuating means being adapted to maintain an engagement between the associated contacts identified with the resilient arm for a preselected interval of time.

5. An interrupter, comprising: a first interrupter arm carrying a contact; a second resilient interrupter arm carrying a contact, mounted on said first arm in ascending spaced relation thereover; a conductive supporting member; a pair of fixed contacts mounted on said supporting member operatively disposed relative to said aforementioned contacts, the set of associated contacts identified with the first arm being normally engaged, and the set of associated contacts identified with the resilient arm being normally spaced; 10 a supporting element mounted on said first arm; a first cam mounted on said supporting element and disposed to engage with the top face side of the resilient arm and operative to vary the spaced relation between said first and resilient arm, said resilient arm being initially tensioned against said cam; and second cam means for actuating said first arm, said second cam means being adapted to maintain an engagement between the associated contacts identified with the resilient arm for a preselected interval of time.

6. An interrupter, comprising: a first interrupter arm carrying a contact; a second resilient interrupter arm carrying a contact, mounted on said first arm radially thereover; an adjustable conductive supporting member; a pair of fixed contacts mounted on said supporting member operatively disposed relative to said aforementioned contacts, the set of associated contacts identified with the first arm being normally engaged, and the set of associated contacts identified with the resilient arm being normally spaced; a supporting element mounted on said first arm; a first cam rotatably mounted on said supporting element and disposed to bear against the top face of the resilient arm and operative to adjust the spaced relation between said first and resilient arms, said resilient arm being initially tensioned against said cam; and a second cam for actuating said first arm, said second cam being constructed and arranged to control an engagement between the associated contacts identified with the resilient arm for a preselected interval of time.

7. An interrupter arm, comprising: a pivotal arm; a second resilient arm having one end supported on said pivotal arm and the other end spaced therefrom, each carrying a contact; and second contacts adapted to be operatively disposed relative to said aforementioned contacts, a set of cooperative contacts being normally engaged and another set of cooperative contacts being normally spaced.

8. An interrupter arm, comprising: a pivotal arm; a second resilient arm cantilever mounted on said pivotal arm; a contact on each of said arms; and second contacts adapted to be operatively disposed relative to said aforementioned contacts, a set of cooperative contacts being normally engaged and another set of cooperative contacts being normally spaced.

9. An interrupter arm, comprising: a pivotal arm; a second resilient arm having one end mounted on said pivotal arm and the remaining portion of said resilient arm disposed in diverging spaced relation to said pivotal arm; a contact

5 on each of said arms; and second contacts adapted to be operatively disposed relative to said aforementioned contacts, a set of cooperative contacts being normally engaged and another set of cooperative contacts being normally spaced.

10. An interrupter arm, comprising: a pivotal arm; a second resilient arm having one end mounted on the back of said pivotal arm and the remaining portion of said resilient arm disposed in ascending spaced relation above said pivotal arm; a contact on each of said arms; and second contacts adapted to be operatively disposed relative to said aforementioned contacts, a set of cooperative contacts being normally engaged and another set of cooperative contacts being normally spaced.

11. The apparatus of claim 8 and means extending from one of said arms engageable with the other of said arms operative to normally limit relative movement of the arms away from each other but permitting free relative movement toward each other.

12. The apparatus of claim 9 and means extending from said pivotal arm engageable with said resilient arm operative to normally limit relative movement of said arms away from each other but permitting movement toward each other.

13. The apparatus of claim 10 and an extension of said pivotal arm engageable with said resilient arm operative to normally limit relative movement of said arms away from each other but permitting free movement toward each other.

14. An interrupter arm, comprising: a first 35 interrupter arm carrying a contact; a second resilient arm carrying a contact, mounted on the back of said first arm and having its free end disposed in spaced relation above the free end of said first arm; a supporting member; a pair of electrically connected fixed contacts mounted on said supporting member and operatively disposed relative to said aforementioned contacts, the set of associated contacts identified with the first arm being normally engaged, and the set of associated contacts identified with the resilient arm being normally spaced; a supporting element mounted on said first arm; and a cam mounted on said supporting element and disposed to engage with the top side of the resilient arm and operative to adjust the spaced relation between said first and resilient arms.

15. An interrupter comprising: an interrupter arm comprising two spaced limbs one of which is resiliently movable relative to the other, a contact on each of said limbs, fixed contacts operatively disposed relative to said aforementioned contacts, a set of cooperative contacts being normally engaged and another set of cooperative contacts being normally spaced, means interconnecting said limbs operative to normally limit relative movement of the limbs away from each other but permitting relative movement toward each other, and means for actuating said interrupter arm, said actuating means being adapted to maintain an engagement between the cooperative contacts identified with the resilient limb for a preselected interval of time.
